UNITED STATES PATENT OFFICE.

HUBERT M. GREIST, OF NEW HAVEN, CONNECTICUT, ASSIGNOR TO THE GREIST MANUFACTURING COMPANY, A CORPORATION OF CONNECTICUT.

SEWING-MACHINE RUFFLER.

1,107,420.

Specification of Letters Patent. Patented Aug. 18, 1914.

Application filed August 4, 1913. Serial No. 782,893.

To all whom it may concern:

Be it known that I, HUBERT M. GREIST, a citizen of the United States, residing at New Haven, in the county of New Haven and 5 State of Connecticut, have invented or discovered certain new and useful Improvements in Sewing-Machine Rufflers, of which the following is a specification, reference being had therein to the accompanying 10 drawings.

This invention relates to that class of sewing machine rufflers adapted to make a plait or gather at each stitch, or, if it be desired to make wider plaits, to form only a single 15 plait while several stitches are being made. Rufflers of this class have generally been known commercially as "five-stitch" rufflers, in that they have heretofore usually been so constructed that when wider plaits are being 20 made they make one gather or plait for each five stitches of the sewing machine; and the present invention has for its object to improve the class of rufflers referred to by the addition of a single simple part which may 25 be so adjusted that when the wider plaits or gathers are being made one plait or gather may be formed for each five stitches of the sewing machine, or for each ten stitches, thus increasing the range of variation of 30 work which may be performed.

Rufflers of the class referred to comprise ratchet wheels having deep and shallow notches forming teeth. Usually each ratchet wheel has two deep notches diametrically 35 disposed on the wheel, with four shallow notches between the deep notches. The operating lever is provided with a pawl or pawls serving to rotate the ratchet wheel and to operate a pendulous lever to which 40 latter the ruffling blade or carrier is connected. By a simple adjustment of the pawl or pawls the ruffling blade may be operated, to form a ruffle or gather, at each vibration of the operating lever which is 45 adapted to be actuated from the needle-bar of the sewing machine; or the ruffling blade may be caused to form one ruffling stroke during each five reciprocations of the needle-bar. Thus when the ruffling blade is caused 50 to act to form a ruffle or gather at each reciprocation of the needle-bar a ruffle or gather will of course be formed at each stitch made by the machine; and when the ruffling blade performs one ruffling stroke 55 during each five reciprocations of the needle

bar a gather or plait will be made only during the formation of each five stitches. The present invention provides an adjustable stop device which, when desired, may be shifted into a position to fill up the inner 60 part of one of the deep notches of the ratchet wheel, so that, with a ten-notch ratchet wheel, and when the parts are adjusted to make wide gathers or plaits, only a single gather or plait will be made during the formation of ten stitches of the sewing machine. This improvement therefore adapts the ruffler for making a gather or plait either at 65 each stitch, at each five stitches, or at each ten stitches of the sewing machine.

In the accompanying drawing Figure 1 is a side view of a well-known form of sewing machine ruffler with the invention applied thereto and showing the parts adjusted for making one ruffle or gather at each five 70 stitches of the sewing machine. Fig. 2 is a view similar to Fig. 1, but showing the parts adjusted for making one ruffle or plait at each ten stitches of the sewing machine. Fig. 3 is a side view of the ruffler 75 opposite to that shown in Figs. 1 and 2 but with the parts adjusted for making a ruffle or gather at each stitch of the sewing machine. Fig. 4 is a detail perspective view of the adjustable stop constituting the present 80 added improvement.

The five-stitch ruffler to which the present improvement is herein shown as being applied is that covered by U. S. Patent No. 1,011,907, dated Dec. 19, 1911, although it 85 will be understood that the present improvement is equally applicable to any form of "five-stitch" ruffler comprising a ratchet wheel having deep and shallow notches.

Referring to the drawing, 12 denotes the 90 body of the frame of the ruffler, and which frame is preferably provided with an integral attaching portion or shank 13 by which it may be secured to the presser-bar of a sewing-machine in substitution of an 95 ordinary presser-foot. The forked operating lever 14 is pivotally mounted on a stud 15 riveted to an upright portion of the frame 12. Also pivotally mounted on the said stud are an oscillating plate 16, a 100 ratchet-wheel 17 and a pendulous or secondary lever 18, the latter being jointed at its lower end to the carrier 19 for the ruffling blade 20. The oscillating plate 16 is 105 provided with a projection 21 engaged by 110

an adjustable regulating screw 22 mounted on the operating lever 14, said oscillating plate having a projection or shoulder 23 adapted to engage a front upper portion of 5 the said pendulous lever for effecting the backward or retractive movements of said lever, and of the ruffling blade connected therewith. The regulating screw 22 permits, according to its position of adjustment, of more or less lost motion between the operating lever 14 and the oscillating plate 16, so that any desired length of stroke may be imparted to the ruffling blade from 10 said operating lever. The pendulous lever 15 18 is provided at its top with a shoulder 24 and the ratchet-wheel is provided with two relatively deep notches 25 between each of which, in the form of the invention herein shown, are groups of four relatively shallow 20 notches 26.

Pivottally mounted on the operating lever 14 are two spring-pressed pawls 27 and 28 which, by means of a partial rotation of the pin or rivet 29, may be brought into horizontal register with each other, as shown in 25 Figs. 1 and 2, when wide plaits or gathers are to be made, or may be separated or thrown out of horizontal register with each other, as shown in Fig. 3, when a ruffle or 30 gather is to be made at each stitch. The pawl 27 coöperates with the shoulder 24 at the top of the pendulous lever 18, while the pawl 28 coöperates with the ratchet-wheel 17 for the purpose of rotating the said ratchet- 35 wheel intermittently when wide plaits or gathers are to be made; the said pawl 28 being thrown out of operation when single-stitch ruffles or gathers are being made. The construction and operation of these parts, 40 performing either single or five-stitch ruffling, is fully set forth in said Patent No. 1,011,907. The ratchet-wheel 17 is frictionally held against backward rotation, when the operating pawls are being retracted, by means of a spider spring 51 rotating with said ratchet-wheel, and interposed between said spider spring and ratchet-wheel, and pivotally mounted on the pin 15, is an adjustable arm or stop 52, of 45 thin spring metal, so as to be adapted to be retained in any desired position of adjustment by its own resilience, said arm or stop rotating with the said ratchet wheel. This arm or stop is provided with a side projection or finger piece 53 for its convenient manipulation, and comprises a stopping part 54 which may be brought into position to fill 50 or close the lower part of one of the deep notches 25 in the ratchet-wheel 17. Thus when the said adjustable arm or stop is in the position shown in Fig. 1 the adjacent deep notch 25 in the ratchet-wheel will be unobstructed; but when the said arm or stop is shifted to the position shown in Fig. 2 55 the lower part of said deep notch 25 will be

partly filled by the portion 54 of the said arm or stop, so that said notch will have a working depth equal to the depth of the shallow notches 26. With the parts thus adjusted, as shown in Fig. 2, the pawl 27 will be held out of engagement with the shoulder 24 on the pendulous lever 18 during the passage of nine of the ten notches in the ratchet-wheel, and can only be lowered into a position to engage said shoulder when the unobstructed deep notch 25 is brought around to a position to be entered by said pawl. From this it will be understood that the ruffling blade 20 will be caused to perform a ruffling stroke only once during a full rotation of the ratchet-wheel 17, and as the said ratchet wheel, in the form of the invention herein shown, is provided with ten notches, only a single gather or plait will be formed during the time when the machine is making ten stitches. Thus the present improvement widens the range of work which may be performed by the use of sewing machine rufflers of the class under consideration, so that such rufflers are adapted to make a ruffle or gather either at each stitch, at each five stitches, or at each ten stitches, as may be desired by the operator.

The invention by which a "five-stitch" ruffler may be changed to a ten-stitch ruffler is not to be understood as being limited to the particular form of the adjustable arm or stop herein shown and by which the working depth of one of the deep notches of the ratchet-wheel may be varied, as the said arm or stop may be different in form and still be adapted to serve its intended function. It will also be understood that the terms "five-stitch" and "ten-stitch" as hereinbefore used are not intended to indicate that the invention is applicable only to a ruffler making relatively wide plaits at either five stitches or ten stitches of the sewing machine, but may have reference to a ruffler employing a ratchet-wheel having a different number of notches than the ratchet-wheel herein shown, so that relatively wide plaits or gathers may be made during the formation of more or less than five stitches or ten stitches of the sewing machine.

Having thus described my invention I claim and desire to secure by Letters Patent:—

In a sewing machine ruffler, the combination with a ruffling blade, of an operating lever, a pawl carried by said lever, a pendulous lever connected with said ruffling blade and provided at its top with a shoulder to be engaged, at times, by said pawl, an intermittently-rotating ratchet-wheel actuated by said pawl and provided with groups of shallow notches which will prevent said pawl from engaging said shoulder and with single deep notches between said groups of shallow notches, and which deep notches

will permit said pawl to engage said shoulder to operate said ruffling blade, and an adjustable arm or stop mounted to rotate with said ratchet-wheel and adapted to be moved into a position, when desired, to fill or obstruct the inner part of one of said deep notches and thus change its working depth and make it practically a shallow notch, and thereby vary the frequency of

movement of the ruffling blade operated through said pawl and pendulous lever.

In testimony whereof I affix my signature, in presence of two witnesses.

HUBERT M. GREIST.
